UNITED STATES PATENT OFFICE

2,475,865

BOTTLE STOP MECHANISM FOR USE WITH
CONVEYERS

Herbert G. Vore, Forest Hills, and Harold W. Martin, Malverne, N. Y., assignors to American Seal-Kap Corporation of Delaware, Wilmington, Del., a corporation of Delaware

Application April 8, 1947, Serial No. 740,182

2 Claims. (Cl. 198—34)

1

This invention relates to bottle capping machines and more particularly to machines for filling and capping milk bottles or the like which include a conveyor for feeding empty bottles to the filling and capping machine and a conveyor conveying the filled and capped bottles from the machine to an inspecting station wherein the bottles are manually placed in cases for shipment or delivery.

An object of the invention is to provide, in a machine of the above type, means under the control of the operator for interrupting the feed of bottles to the filling machine so that if for any reason the bottles become stacked up at the inspecting station, the feed of bottles may be interrupted until the operator is ready to receive more bottles.

Another object is to provide a device of the above type which automatically accommodates itself to bottles of various sizes.

Another object is to provide a control gate for interrupting the feed of bottles along the conveyor, which is controllable by the operator from a remote point.

Various other objects and advantages will be apparent as the nature of the invention is more fully disclosed.

In accordance with the present invention a control gate is provided in the form of a swinging arm having a cam surface to be engaged by the container when the arm is swung into the path of the advancing container. The cam surface terminates in a shoulder which engages the container and prevents the advance thereof by the conveyor. The cam surface is arranged to accommodate the gate to containers of various sizes. The arm is spring-biased into feed interrupting position, but is retractable by a control linkage actuated by a control handle at a remote point which is conveniently located to the operator.

Although the novel features which are characteristic of this invention are pointed out more particularly in the claims, the nature of the invention will be better understood by referring to the following description, taken in connection with the accompanying drawings forming a part thereof in which a specific embodiment of the invention has been set forth for purposes of illustration.

In the drawings:

Fig. 1 is a top plan view of a container filling and capping machine and conveyor system therefor embodying the present invention;

Fig. 2 is a top plan view of the stop mecha-

2

nism on a larger scale taken from the filling machine side of the conveyor;

Fig. 3 is a side elevation of the stop mechanism of Fig. 2;

5 Fig. 4 is a vertical transverse section taken on the line 4—4 of Fig. 3;

Figs. 5 and 6 are top plan views of the stop mechanism showing different positions of the gate;

10 Fig. 7 is a partial plan view similar to Fig. 2, but illustrating the stop mechanism as actuated by a solenoid;

Fig. 8 is a side elevation of the manual control mechanism;

15 Fig. 9 is a top plan view of the manual control mechanism of Fig. 8;

Fig. 10 is a horizontal section taken on the line 10—10 of Fig. 8; and

Fig. 11 is a vertical transverse section taken 20 along the line 11—11 of Fig. 8.

Referring to Fig. 1 more in detail, the invention is shown for illustration as applied to a filling and capping machine of the type shown in the Goodwin et al. Patent No. 2,375,163 dated

25 July 27, 1943 which includes in general an empty container conveyor 15 for feeding empty containers for filling and capping to the machine, a filling turret 16 to which the containers are fed from the conveyor 15 by means of a star wheel 17, a cap-applying station 19 at which caps are applied to the filled containers, a capping turret 30 having capping heads for contracting the cap skirts about the necks of the containers for sealing, and a star wheel 31 feeding the

30 capped containers to a filled container conveyor 32 which leads to an inspection and loading platform 34. An operator stands near the platform 34 and manually places the containers in cases carried on a case conveyor 35.

35 The caps are supplied to the cap applying station 19 from a cap magazine 20 by picker mechanism 22 which is actuated in response to a switch 23 controlled by a container-actuated arm 24 and feeds the caps to a conveyor 21 terminating 40 at the station 19. A plurality of stacks 25 are successively brought into registration with a magazine 20 by means of a turret 26.

45 Inasmuch as the details of the filling and capping machine form no part of the present invention only so much thereof has been disclosed herein as is necessary to an understanding of this invention.

It frequently happens in the operation of machines of this type that the capped containers ac-

55 cumulate on the inspection platform 34 faster

than they can be removed and placed in cases by the operator. When this occurs it is necessary for the operator to stop the machine temporarily. However, starting and stopping the machine is a time-consuming operation and in the case of machines of the type above referred to in which the caps are applied to the containers with a heated thermoplastic sealing compound on their skirts, stopping the machine with bottles and caps in transit therethrough results in a number of improperly capped containers which must be returned for recapping.

In order to overcome this difficulty the present invention provides a gate in the form of a swinging arm 40 which is mounted to register with the advancing containers on the conveyor 15 in the manner to be described. This arm 40 is shown in Fig. 1 as actuated by a link 41 which in turn is controlled by a handle 42 conveniently located to the operator at the inspection table 34. The arrangement is such that by actuation of the handle 42, the operator may stop the incoming containers at the gate 40 while allowing the machine to continue operating so that any containers in transit in the machine at the time are capped and delivered to the table 34. When the operator is ready to receive more containers, the gate 40 is released by actuation of the handle 42 to again admit containers to the filling and capping machine.

Referring to Figs. 2 to 6, the gate 40 is shown as mounted on a pin 45 which is pivoted in a bracket 46 attached to the frame 47 carrying the conveyor 15. The pin 45 carries at its lower end an arm 50 which is connected to the link 41 by a yoke 51. The arm 50 is biased to the container stopping position by means of a spring 52 which is attached to a fixed bracket 53. The gate 40 is provided with a cam surface 55 which is adapted to be engaged by a container 56 on the conveyor 15. The cam surface 55 terminates in a shoulder 57. The cam surface 55 is designed at such a slope that when it is engaged by a container 56, the arm 40 is cammed outwardly by the container until the container engages the shoulder 57. Thereafter the shoulder provides a stop to limit further feed of the container 56 on the conveyor 15.

In Figs. 2, 5 and 6 square containers have been shown for purposes of illustration. It is to be understood, however, that the shoulder 57 is so designed that it will be actuated by round containers in the same manner.

The arrangement is such that when the link 41 is released spring 52 swings the gate 40 into the path of the advancing container on the conveyor 15 as illustrated in Fig. 2. In this figure a small container such as a pint milk bottle is shown on the conveyor 15. The container may be assumed to have any position across the conveyor. Whatever the position of the container 56, when the same reaches the cam surface 55 it is caused to slide over against the outer rail 59 of the conveyor. Thereafter the gate 40 is cammed outwardly by the container until the container engages the shoulder 57 and is held thereby against further movement.

Figs. 5 and 6 illustrate the action of the gate for large size containers 60 such as quart milk bottles. Referring to Fig. 5 it will be noted that the gate 40 has been swung inwardly over the conveyor 15. When the container 60 reaches the cam surface 55 of the gate 40, the gate is cammed outwardly until the position shown in Fig. 6 is reached, whereupon the container engages the shoulder 57

and is brought to rest. It will be noted, therefore, that the gate may be operated without adjustment to accommodate various sizes and shapes of containers and in any case will cause the container to come to rest against the shoulder 57.

The manual control mechanism, including the handle 42, is shown in Figs. 8 to 11 as comprising an arm 61 which is pivoted by a pin 62 to a plate 63 carried by the conveyor frame. The arm 61 carries a yoke 64 which is pivoted thereto by a pin 65 and carries the link 41. The plate 63 is provided with a recess 66 to afford clearance for the yoke 64. At the upper end of the arm 61 a pawl 68 is pivoted by a pin 69. The pawl 68 is provided with a finger 70 which engages a detent 71 formed at the top surface of the plate 63. The end of the pawl 68 opposite the finger 70 carries the handle 42.

In normal operation the arm 61 is moved to its right hand position as seen in Fig. 8 with the pawl finger 70 engaged in the detent 71, thereby causing the arm 61 to actuate the link 41 and pull the gate 40 out of registration with the advancing containers on the conveyor 15. When the operator desires to interrupt the feed of the containers it is only necessary to press downwardly on the handle 42 thereby releasing the pawl finger 70 from the detent 71 and permitting the arm 61 and the gate 40 to be swung into feed-interrupting position by means of the spring 52. When it is desired to release the gate 40 for restoring the advance of the containers, the handle 42 is pulled to the right and upwardly as seen in Fig. 8 thereby restoring the arm 61 to its right hand position and engaging the pawl finger 70 in the detent 71. The gate 40 is thus pulled out of the path of the containers against the tension of the spring 52 and the containers are released for feeding by the conveyor 15.

In the modification shown in Fig. 7 the arm 50 is shown as connected to a link 80, connected to a solenoid 81 which is arranged to bring the arm 40 out of feed-interrupting position when the solenoid 81 is energized. A suitable electric circuit (not shown) may be connected to a switch located conveniently to the operator for de-energizing the solenoid 81 when it is desired to interrupt the bottle feed.

Although a specific embodiment of the invention has been shown for purposes of illustration, it is to be understood that various changes and adaptations may be made therein as will be readily apparent to a person skilled in the art. The invention is only to be restricted in accordance with the scope of the following claims.

What is claimed is:

1. A container stop mechanism to interrupt the advance of containers on a conveyor, comprising an arm pivoted to swing about a vertical axis with its free end extending toward the advancing containers, said free end having an inclined cam surface terminating in a shoulder shaped to engage and hold said container against further advance, a spring urging said arm into stop position, said cam surface being shaped to engage and position the advancing container against the side of said conveyor opposite said arm and then retract said arm to accommodate the size of the container until the container is brought to rest against said shoulder, and remote manual retractor means connected to normally hold said arm retracted from the path of the containers, said manual means being releasable to allow said spring to advance said arm into stop position.

2. A container stop mechanism as set forth in claim 1 in which the manual retractor comprises a pivoted lever, a link connecting said lever to said arm, a latch on said lever to hold said arm retracted and a manual control to release said latch.
